PERPETUAL CALENDAR

William S. Sherman, Highland Park, Ill., assignor to The Autopoint Company, Chicago, Ill.

Filed Aug. 18, 1969, Ser. No. 18,731

Term of patent 14 years

Int. Cl. D19—03

U.S. Cl. D74—5

FIG. 1.

FIG. 2.

FIG. 3.

FIG. 4.

FIG. 5.

FIG. 6.

FIG. 1 is a perspective view of a perpetual calendar embodying my new design;

FIG. 2 is a front elevational view thereof;

FIG. 3 is a side elevational view thereof;

FIG. 4 is a side elevational view of the side opposite that of FIG. 3;

FIG. 5 is a top plan view thereof; and

FIG. 6 is a rear elevational view thereof.

The dominant features of my design reside in the base portion.

I claim:

The ornamental design for a perpetual calendar, substantially as shown and described.
